(57) CLAIM

The ornamental design for a wine cork with ornamental label, as shown and described.

DESCRIPTION

FIG. 1 is a front perspective view of a wine cork with ornamental label showing my new design;

FIG. 2 is a rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a detailed view of a first variant of the ornamental label for the wine cork of FIG. 1; and,

FIG. 8 is a detailed view of a second variant of the ornamental label for the wine cork of FIG. 1.

WWW.DRYCREEKVINEYARD.COM is a registered domain name of Dry Creek Vineyard of Healdsburg, CA and forms no part of the claimed design. The broken lines shown in the figures form no part of the claimed design.
